BED

John Henry De Boer, Syracuse, N. Y.

Application February 13, 1936, Serial No. 63,769

2 Claims. (Cl. 5—131)

Important objects of the present invention are to provide, in association with the main frame of a bed, satisfactory auxiliary means to support the weight of the bed springs, the mattress and the occupants of the bed independently of the main frame in order to relieve the latter of strain and also enable the entire bed to be shifted easily upon the floor, and to provide such auxiliary means in the form of a frame supported on 10 casters and designed to readily fit into the enclosure defined by the main frame and to shift easily upon the floor along with the main frame.

Other objects of the invention will appear hereinafter.

15 In the drawing,

Fig. 1 is a perspective view of a main bed frame and the auxiliary frame fitted within the enclosure defined by the main frame to support the springs and mattress, one of the side rails of the 20 bed being broken away and also shown detached from the head of the main frame;

Fig. 2 is a cross-sectional view of the completely 25 assembled bed, showing the auxiliary frame supporting the springs and mattress independently of the main frame; and

Fig. 3 is a group view showing a number of the 30 details of the auxiliary frame in perspective.

There is shown in the drawing a main bed frame of conventional construction. Said frame 35 includes a head panel 1, a foot panel 2 and side rails 3. The head and foot panels have legs provided with casters 4. Preferably there are quickly releasable joints between the side rails and the head and foot panels enabling either side 40 rail to be removed. Said joints may, as shown, be of a usual construction, including downwardly opening hooks 5 borne by the ends of the rails and lockably fittable into keeper slots 6 in the head and foot panels. In the present instance, the removability of the side rails has a special 45 advantage which will appear hereinafter.

For the support of the weight of the bed springs, the mattress and the occupant there is provided a rolling carrier which is disposable 50 within the enclosure defined by the main frame. It is self-supporting upon the floor and is constructed to support all of the said weight independently of the main frame.

The carrier for the bed springs and the mattress 55 comprises an auxiliary frame formed to fit freely between the side rails of the main frame. The structure of the auxiliary frame includes four short corner posts 7 bearing casters 8, preferably of liberal diameter. At their upper ends the posts have a cleft 9. Two longitudinal side

rails 10 have their opposite ends fitted snugly in said clefts and releasably secured by bolts 11 passed through bores in the cleft ends of the posts, and in the ends of the longitudinal rails, and have nuts 12 screwed thereon. The posts are connected, across the frame, by transverse end rails 13. The latter are releasably secured to the posts which they connect by bolts 14 and nuts 15. Preferably, the joint between each rail and post includes two of the bolts 14 passed through bores in the rail and bores in the post, located at opposite sides of the cleft 9. Preferably, the upper edges of the side rails 10 and of the end rails 13 are flush with the upper ends of the posts. Each side of the auxiliary frame includes a flat longitudinal top rail 16 lying flat upon the side rail 10 and upon the upper ends of the posts and protruding across the upper edges of the end rails 13. These top rails are secured to the upper ends of the posts by screws 17 passed through bores in the top rails and screwed into the posts. There are preferably two of these screws at each post and located at opposite sides of the cleft 9. All joints between the posts of the frame are releasable so that the 20 frame can be knocked down for storage or shipping and it can be readily set up where it is to be used.

The carrier for the springs and mattress is proportioned to nest easily into the main frame of the bed. The top rails 16 are materially shorter than the side rails 10 of the main frame, and the length of the end rails 13 is slightly less than the inside width of the main frame, that is the width between the side rails 3. The height of the carrier with relation to the side rails 3 of the main frame is such that the rails 10, 13, and 16 will be confined and laterally concealed by the main frame, and the ends of the cross rails 13 will form abutments to engage the inner 30 sides of the rails 3 and limit relative transverse shift of the nested frames. Preferably, as shown, the posts 7 are spaced inwardly from the ends of the rails 13 to position the posts and their casters in 35 unobstructing positions and render them inconspicuous.

The carrier is of a strong construction capable of supporting the entire weight of the springs, the mattress and one or more occupants of the bed. The spring assembly 8 is placed upon the 40 top rails 16 of the carrier. Since the carrier is unsecured to the main frame the latter is entirely relieved of the strain of said weight. That enables the main frame to be made of quite light construction, if desired. Also, the firm support 45

afforded by the carrier gives the occupant a feeling of security.

Another important advantage is that the bed may be more easily shifted than when the springs and mattress are supported by the main frame. 5 The addition of the carrier with its casters gives eight points of rolling support for the bed assembly instead of the usual four points, with consequent reduced concentration of weight at 10 the points of support and reduced wear upon carpet or rugs when the bed is shifted. Owing to the large size of its casters, the carrier will roll quite easily, and owing to the fact that the carrier frame is confined within the main frame, 15 the entire assembly may be shifted or rolled as a unit by application of force to the main frame. Upon removal of one of the side rails of the main frame, the carrier, with the springs and mattress thereon may be rolled out of the main frame, 20 for easy access to the springs or in order to position the mattress so that it can be turned conveniently.

While I have disclosed a very satisfactory form of the invention, it will be obvious that structural details may be modified without departing from 25 the spirit of the invention as defined in the appended claims.

I claim:

1. A bed including a main frame comprising 30 head and foot members and side rails one of which rails has quickly releasable joint connections with the head and foot members for detachment

of said rail from the main frame assembly, and anti-friction elements to support said frame upon the floor; and an auxiliary frame disposed within the enclosure defined by said main frame and confined by the latter frame against lateral withdrawal from the enclosure and having anti-friction elements to support it upon the floor and being constructed and arranged with relation to the main frame for supporting the entire weight of the bed springs, mattress and occupant of the bed independently of the main frame, the said two frames being also formed with relation to each other to permit sidewise moving of the auxiliary frame upon its anti-friction supporting elements and with springs and mattress thereon out 10 from the main frame upon removal of said detachable side rail of the main frame, and the frames in their assembled relation being free for support of each frame entirely by its own anti-friction supporting elements. 15

2. A bed according to claim 1, characterized in 20 that the auxiliary frame comprises four corner posts each with a caster at its lower end and a cleft in its upper end, a pair of opposite side rails having their ends detachably secured within the 25 clefts of said posts, a pair of opposite end rails extending across the post clefts and the ends of said side rails and detachably secured to the posts, and top rails resting upon and secured to the upper ends of the posts. 30

JOHN HENRY DE BOER.
